UNITED STATES PATENT OFFICE

99,477

DESIGN FOR A KNITTED FABRIC

Harry Fleisher, Watertown, Conn., assignor to Princeton Inc., Watertown, Conn., a corporation of Connecticut

Application January 23, 1936, Serial No. 60,741

Term of patent 7 years

To all whom it may concern:

Be it known that I, Harry Fleisher, a citizen of the United States and residing at Watertown, in the county of Litchfield and State of Connecticut, have invented a new, original, and ornamental Design for Knitted Fabrics, of which the following is a specification, reference being had to the accompanying drawing, forming part thereof.

Fig. 1 is a plan view of one side of the knitted fabric, showing my new design.

Fig. 2 is a plan view of the reverse side thereof.

I claim:

The ornamental design for a knitted fabric, as shown.

In testimony whereof, I have affixed my signature to this specification.

HARRY FLEISHER.
